1987.

[**] Term: 14 Years

Primary Examiner—Robert C. Spangler
Attorney, Agent, or Firm—Parkhurst & Oliff

[21] Appl. No.: 760,419

[57] CLAIM

[22] Filed: Jul. 30, 1985

The ornamental design for a container wall, as shown
and described.

[52] U.S. Cl. D9/392; D9/396;
D9/406; D9/411; D9/434

DESCRIPTION

[58] Field of Search D9/349, 350, 351, 352,
D9/355, 390, 392, 394, 396, 397, 398, 399, 401,
404, 406, 410, 411, 434; 215/1 R, 1 C

FIG. 1 is a side elevational view of a container wall
showing my new design;

[56] References Cited

FIG. 2 is a top perspective view on a reduced scale, the
opposite side being the same in appearance; and

U.S. PATENT DOCUMENTS

FIG. 3 is a top perspective view showing a modified
form of my new design, the opposite side being the same
in appearance.

- D. 63,324 11/1923 Root D9/398
D. 64,124 3/1924 Miller D9/398
D. 77,054 12/1928 Bramble D9/397
D. 229,541 12/1973 Anderson D7/378
D. 234,292 2/1975 Plummer D9/355

The broken lines showing a container top and bottom
are for the purpose of showing environmental structure
only.

FOREIGN PATENT DOCUMENTS

The container wall of the invention is symmetrical so
that all side views present the same appearance.

497982 3/1979 Japan .
